(57) **CLAIM**

The ornamental design for the bowl with lid, as shown and described.

DESCRIPTION

FIG. 1 is an isometric view of a bowl with lid in accordance with our new design;

FIG. 2 is a front elevation view of the bowl with lid shown in FIG. 1;

FIG. 3 is a rear elevation view of the bowl with lid shown in FIG. 1;

FIG. 4 is a right side elevation view of the bowl with lid shown in FIG. 1;

FIG. 5 is a left side elevation view of the bowl with lid shown in FIG. 1;

FIG. 6 is a top plan view of the bowl with lid shown in FIG. 1;

FIG. 7 is a bottom plan view of the bowl with lid shown in FIG. 1;

FIG. 8 is a somewhat enlarged cross sectional view taken along line 8-8 of FIG. 6, wherein the thin lined cross hatched portion of the lid designates that portion is opaque or translucent, whereas the alternating thin and thick lined cross hatched portion of the lid and the alternating thin and thick lined cross hatched portion of the bowl designates that those portions are transparent;

FIG. 9 is an isometric view of FIG. 1 shown with the lid removed;

FIG. 10 is a front elevation view thereof;

FIG. 11 is a rear elevation view thereof;

FIG. 12 is a right side elevation view thereof;

FIG. 13 is a left side elevation view thereof;

FIG. 14 is a top plan view thereof;

FIG. 15 is a bottom plan view thereof;

FIG. 16 is an isometric view of FIG. 1 shown with the bowl removed;

FIG. 17 is a side elevation view thereof, the side view being the same from any direction;

FIG. 18 is a top plan view thereof;

FIG. 19 is a bottom plan view thereof; and,

(Continued)

FIG. 20 is a somewhat enlarged cross sectional view taken along line 20-20 of FIG. 19, wherein the thin lined cross hatched portion of the lid designates that portion is opaque or translucent.

The broken lines in the various figures are directed to unclaimed portions of the bowl with lid and form no part of the claimed design.
